No. 759,664.

PATENTED MAY 10, 1904.

J. E. BUEHLER.
ROLLER WINDOW SCREEN.
APPLICATION FILED APR. 25, 1903.

NO MODEL.

UNITED STATES PATENT OFFICE.

JOSEPH E. BUEHLER, OF NEW YORK, N. Y.

ROLLER WINDOW-SCREEN.

SPECIFICATION forming part of Letters Patent No. 759,664, dated May 10, 1904.

Application filed April 25, 1903. Serial No. 154,331. (No model.)

To all whom it may concern:

Be it known that I, JOSEPH E. BUEHLER, a citizen of the United States, residing at New York, in the State of New York, have invented 5 a new and useful Roller Window-Screen, of which the following is a specification.

This invention relates generally to window-screens, and more particularly to a casing for containing a window-screen which is connected to the window-sash, so that when the sash is raised or lowered the screen will be withdrawn from its casing and fill the intervening space between the sash and window-frame.

Various constructions of cases and means 15 for connecting the screens to the window frames and sashes have been devised; but these cases and means have not generally been made adjustable to suit various widths of windows.

The object of my invention, therefore, is to 20 provide a screen-casing which shall be adjustable, whereby it can be fitted to any window-frame; and another object is to provide adjustable means both within the casing and upon the window-sash for the purpose of securing 25 the screen.

With these objects in view the invention consists in the peculiar construction of the various parts and in their novel combination and arrangement, all of which will be fully 30 described hereinafter and pointed out in the claims.

In the drawings forming part of this specification, Figure 1 is a view showing the practical application of my invention, the screens 35 being applied to both the upper and lower ends of the window-frame. Fig. 2 is a vertical sectional view illustrating the arrangement of the various parts. Fig. 3 is a horizontal sectional view of the casing and roller. Fig. 40 4 is a detail perspective view showing one of the journal-brackets for the screen-roller, the rod being detached from the socket-stud. Fig. 5 is a transverse sectional view taken through one of the upper roller-brackets, the position 45 of the roller and screen being indicated in dotted lines. Fig. 6 is a detail perspective view of one of the adjustable clamping-strips employed to connect the end of the screen to the window-sash. Fig. 7 is a transverse section 50 view of the said clamping-strip; and

Fig. 8 is a detail sectional view illustrating the means of connecting the strip upon the screen.

Referring to the drawings, A indicates the window-frame, B the upper sash, and C the lower sash, all of which may be of the usual or any preferred construction. At the upper end of the window-frame and also at the lower end I arrange cases D, which are intended to contain the screens E when not in use, the upper screen E being connected at its free end to the upper end of the lower sash, while the lower screen E is connected at its free end to the lower end of the lower sash, as most clearly illustrated in Fig. 2. In 60 making these connections I employ a special construction of screen and also special constructions of rollers and means for fastening the screens to the window-sashes. These features are the essential points of my invention, and in constructing the said parts I employ box-like roller-brackets F, having ears or lugs F' for attachment to the window-frame. Each roller-bracket is also provided with an inwardly-projecting stud F'', one of said studs 70 being threaded, as shown at F'', to receive a rod G. The box-like brackets F are open at one side, as most clearly shown, the opposite side being formed with a guide F' for the purpose of guiding the edge of the screen as 75 it is rolled upon the roller. The box-like brackets F are secured at the upper and lower ends of the window-frame, at the sides thereof, and a metallic case H is fitted between the 80 said brackets, said case being preferably square 85 in cross-section and of such size as to snugly fit within the bracket F, said case having a slot H', which registers with the guide F', so that the screen can pass freely in or out of the case, as desired. The case H is preferably 90 made in two or more sections telescoping into each other, as most clearly shown in Fig. 3, so that the said case can be made to fit any width of window-frame. A roller I is arranged within the case, said roller being 95 preferably tubular in form and journaled upon the studs F'', and this roller I is also made in sections which may be connected by means of a supplemental roller I'. The rod G extends a considerable distance into one 100

end of the roller I, and a coil-spring K is arranged within the tubular roller I and surrounds the said rod G, one end of said spring being secured to the inner end of the rod, 5 while the other end of the spring is secured to the roller, thereby producing a spring tension upon the roller for the purpose of keeping the screen sufficiently tight at all times. The screen E is fastened at one end to roller 10 I in any suitable manner. The opposite end of the screen is preferably secured to a metallic strip L, which is secured within the clamp-strip, fastened to the window-sash by means of the perforated ears or lugs L', 15 said clamp-strip being essentially in the form of an inverted U with a compressed opening, so as to securely bind the end strip of the screen, and this clamp-strip L is also made in telescopic sections, so that it can be 20 made to fit any width of window-sash. As before stated, the clamp-strip is fastened to the window-sash, the one connected to the lower screen being attached to the bottom rail of the lower sash, while the one connected 25 to the upper screen is connected to the top rail of the upper sash.

While I have shown and described two screens—namely, the upper and lower ones—it will of course be understood that only one 30 screen can be employed, if desired, and that either an upper or lower one can be used, as occasion may require.

In the practical application of my invention the casing will be applied to the window-frame, after being properly adjusted, by securely connecting the box-like brackets to the window-frame, no other connection being necessary. The clamp-strips are then adjusted and secured to the window-sash and the end 35 of the screen secured therein. The device is 40 then ready for operation, and it will be readily understood that as the sash is raised or lowered the screen will be rolled or unrolled from the case and will always screen the space intervening between the rail of the sash and the window-frame.

Having thus fully described my invention, what I claim as new, and desire to secure by Letters Patent, is—

50 1. In a device of the kind described, the combination with the adjustable case provided with

inwardly - projecting studs, of a sectional spring-actuated roller mounted on said studs, said sections being connected by a supplemental roller, the adjustable sectional clamping-strip, the sections of which are approximately inverted-U-shaped, and the screen having one of its ends secured between the members of said clamping-strips and the other end connected to said roller, substantially as shown 55 60 and described.

2. In a device of the kind described the combination with the box-shaped roller-bracket, provided with ears and with inwardly-projecting studs, one of said studs being threaded, a rod secured in said stud and having a coiled spring surrounding its projecting end, said spring having one of its ends secured to said rod and the other to the roller, a sectional roller journaled on said studs, said roller carrying a screen, the free end of which is secured in the sectional clamping-strip, said strip being provided with ears, substantially as described.

3. In a device of the kind described, the combination with the box-like brackets having guides and also provided with inwardly-projecting studs, the sectional telescopic case arranged between the box-like brackets, the tubular adjustable roller journaled upon the 80 studs, the coil-spring arranged within the roller and adapted to exert a torsional strain thereon, and the adjustable clamping-strip provided with perforated ears or lugs, and the screen arranged between the said strip and 85 the spring-actuated roller, substantially as described.

4. The combination with the box-like brackets having guides and studs, of the sectional telescopic case arranged between the brackets, 90 the sectional tubular roller journaled upon the studs and the brackets and rod secured to one of the studs and projecting into the roller, a coil-spring surrounding the rod and attached thereto at one end, the opposite end of said 95 spring being connected to the roller all arranged and adapted to operate substantially as described.

JOSEPH E. BUEHLER.
